HENRY DRAGNER AND LOUIS J. HARRIS, OF NEW YORK, N. Y.

PHONOGRAPH-TABLE.

1,388,243.

Specification of Letters Patent. Patented Aug. 23, 1921.

Application filed October 22, 1919. Serial No. 332,544.

To all whom it may concern:

Be it known that we, HENRY DRAGNER and LOUIS J. HARRIS, citizens of the United States of America, residing at New York city, in the county of New York and State of New York, have invented certain new and useful Improvements in Phonograph-Tables, of which the following is a specification.

10 Our invention relates to an improved phonograph table and has reference particularly to means for controlling the action of the motor board and the upper cover board during the opening and closing of the table.

15 The principal object of our invention is to facilitate the operations of opening and closing the table, and to so construct the means adapted to this purpose that the 20 motor board may be opened and closed without shock or jar and in its movements will control the opening and closing of the upper cover.

25 The preferred form of the invention is illustratively exemplified in the accompanying drawing in which—

Figure 1 is a perspective view of our phonograph table in open position;

30 Fig. 2 is a substantially central, vertical sectional view showing the table in closed position;

Fig. 3 is a perspective view of a detail; and

35 Fig. 4 is a similar view of the bar which carries the upper cover board.

40 In the drawing, the letter A denotes the table generally which is provided with a compartment B, open at the front and bottom, designed to receive the motor board, the phonograph and the horn, held thereon.

45 10 denotes what is generally termed the motor board, being a board or shelf on which the disk 11 is carried and having suspended therebelow the motor 12 for driving the disk. The motor board also supports the tone-arm C which is designed to travel over the disk 11, and the horn or amplifier D which depends in the chamber B below the motor board. Depending from the front 50 edge of the motor board 10 is a lower front member 13 through which extends the actuating shaft 14 of the motor carrying at its front end the crank or winding handle 15.

55 Mounted in the bottom of the compartment B at opposite sides thereof are pairs of like cleats 16 each of which is designed

to pivotally receive the crank end of a substantially U-shaped rectangular bar 17, and on the under face of the motor board 10 are similar cleats 16^a in which the opposite straight portions of the U-bars 17 are pivotally contained. It will be noted, especially from Fig. 1, that there are 4 cleats on the under face of the baseboard 10 and a like number on the lower ledges B' of the 65 compartment B.

Secured to the motor board 10 is one end of a coiled spring 18, the other end thereof being secured to one side of chamber B. The spring is provided to balance the movement of the motor board 10 during the opening and closing of the cabinet. In one of the side walls of the chamber B we provide 70 a block 19 in the path of the motor board, said block serving as a support for the motor board when extended and also to prevent the motor board from projecting too far out of the chamber B.

The upper cover board is denoted 20 and is pivotally carried by a U-shaped bar 21⁸⁰ having short crank arms 21^a each having one of its ends bearing in a side wall of the chamber B. A block 22 in one of the side walls of the chamber B acts as a stop to limit the movement of the cover 20. 85

Secured to one of the lateral edges of the motor board 10 intermediate its ends is an angle piece 23 to which is pivotally attached a sleeve or open socket 24, and pivotally secured to the upper end of one of the lateral edges of the cover is a link 25 pivotally connected to a second link 26 adapted to move about a pivot 26^a provided in the side walls of the compartment B and said link is guided in the socket 24, carried by the 90 angle member 23 and motor board 10. 95

The operation of the structure described is substantially as follows:—In the closed position, as shown in Fig. 2, the several parts occupy the respective positions indicated by the full lines, while in the open position the parts occupy the respective positions indicated by the dot and dash lines. Assuming the table to be closed, in order to open the same pull is exerted on the crank handle 15 whereby the U-bars 17 will rock in the cleats 16, and these U-bars will move substantially in the arc of a circle as the motor board moves outwardly and downwardly. During this motion of the motor board and guide socket 2 the link 26 will be moved about its pivot 26^a imparting a relative 105 motion to the upper cover board 20. 110

tive rearward movement to the link 25 into the dotted line position thereby moving the crank arms 21 rearwardly and backwardly so as to move the cover board 20 into a position approximately parallel to the upper wall of the chamber B, as shown in full lines in Fig. 1. The phonograph table is thus completely opened and the motor board is firmly supported so that there is substantially no vibration when the phonograph is playing. To close the table it is merely necessary to move the motor board rearwardly whereby the parts will move in a reverse direction to that above described and causing the several parts to assume the full line position of Fig. 2.

It is especially important to note that we eliminate all shocks and jars to the phonograph by our construction, and enable the parts to be easily manipulated without any substantial exertion.

What we claim is:—

1. A phonograph table having a partially open compartment therein, a motor board movably supported in said compartment, pivotally mounted supports for said motor board and adapted to sustain the latter in a level plane, an upper cover board, and means connecting the cover board and motor board whereby forward and rearward movement of the latter will control the arcuate and lateral movement of the former.

2. A phonograph table having a partially open compartment therein, a pair of bars pivotally mounted in said compartment, a motor board carried at a level plane by said bars, an upper cover board pivotally supported above said motor board, and means connecting the cover board and motor board

whereby forward and rearward movement of the latter will control the arcuate and lateral movement of the former.

3. A phonograph table having a partially open compartment therein, a pair of substantially U-shaped bars pivotally mounted in said compartment, a motor board mounted on said bars, a third U-shaped bar pivoted above said first mentioned bars, an upper cover board supported by said third bar, a sleeve pivotally supported by said motor board, a pivoted link slidable in said sleeve, and a second link pivoted to said first named link and having a connecting means to said cover board whereby movement of the motor board will control the movement of the cover board.

4. A phonograph table having a partially open compartment therein, a pair of substantially U-shaped bars pivotally mounted in said compartment, a motor board mounted on said bars, a third U-shaped bar pivoted above said first mentioned bars, an upper cover board supported by said third bar, a sleeve pivotally supported by said motor board, a pivoted link slidable in said sleeve, a second link pivoted at one end to said first named link and having its other end pivoted to said cover board whereby movement of the motor board will control the movement of the cover board, a spring for balanceing the opening and closing movement of the motor board, and stops for the motor board and cover board, respectively.

In testimony whereof we have affixed our signatures.

HENRY DRAGNER.
LOUIS J. HARRIS.
